BOILER

Rudolf M. Ostermann, Kenilworth, Ill., assignor
to The Superheater Company, New York, N. Y.Application December 17, 1931
Serial No. 581,577

10 Claims. (Cl. 122—481)

This invention relates to boilers equipped with superheaters, particularly boilers in which the fire-box is enclosed by water-cooled surfaces as in the case of the ordinary locomotive boiler. 5 The purpose of the invention is to provide a superheater in such a boiler which will furnish steam of the high superheat desired in modern practice and yet protect the superheater against excessive heating particularly at times when no 10 steam is flowing through it.

The invention is illustrated in the accompanying drawings. In these drawings Fig. 1 represents a vertical longitudinal section of a locomotive with my invention applied. Fig. 2 shows 15 at the left a section on line 2—2 of Fig. 1 and at the right a fragmentary top view of Fig. 1. Fig. 3 shows at the left a section on line 3a—3a of Fig. 1 and at the right a section of the same figure on line 3b—3b. Fig. 4 is an enlarged section 20 on line 4—4 of Fig. 1. Fig. 5 shows one of the elements of the superheater according to my invention, the left hand portion of it being shown in vertical section, on line 5—5 of Fig. 4, this part also showing the means of securing the unit 25 to the crown sheet of the boiler. Fig. 6 is a section on line 6—6 of Fig. 5. Fig. 7 is a vertical longitudinal section of the rear portion of a locomotive boiler with my invention, in modified form, in place. Fig. 8 is an outside half-view 30 of Fig. 7 looking toward the right. Fig. 9 is a half-section on line 9—9 of Fig. 7. Figs. 10 and 11 are respectively sections on lines 10—10 and 11—11 of Fig. 8. Fig. 12 is an enlarged fragmentary view of one of the superheater elements 35 bringing out particularly the means of attachment of the element to the crown sheet; and Fig. 13 is a section on line 13—13 of Fig. 12.

The locomotive boiler shown in Fig. 1 for the 40 purpose of illustrating my invention is of the ordinary type. It comprises the fire-box 1 which is surrounded on all sides except the bottom by water-cooled surfaces. The crown sheet 2 defines the top of the fire-box, this crown sheet 45 being extended downward at the sides as at 3 (Fig. 4) to form the inner sides of the fire-box. From the rear flue sheet 4 extend forward the flues 5—5, their front ends being secured to the front flue sheet 6. These flues open into the smoke-box 7. The gases coming from the fire-box 1 pass through the flues 5—5 into the smoke-box 7 and finally out through the smoke stack 8.

The ordinary superheater as used almost universally today comprises tubular elements whose 50 ends are connected to a superheater header, the header being located in the smoke-box and the

tubular elements extending into the flues toward the fire-box and to a point in proximity to the rear flue sheet. With such superheaters the amount of superheat that can be obtained has a rather definite limit and when higher temperatures are desired, further provisions for superheating must be made. I propose to do this by locating some of the superheating surface or, in some cases, perhaps all of the superheating surface in the fire-box. In the form of my invention 60 illustrated in Figs. 1 to 6, I combine such a fire-box superheater with a flue superheater of the old type. In the second form of my invention illustrated in Figs. 7 to 13, the superheating surface in the fire-box may be the only superheating 65 surface on the locomotive although here too it may, if desired, be combined with superheating surface placed in the flues.

Referring first to the form of the invention illustrated in Figs. 1 to 6, I show some superheating 70 elements designated by the reference numeral 9, these units of elements being of an ordinary form and extending into some of the flues 5—5. The forward ends of the elements are connected to the superheater header 10. This portion of the 75 header to which the elements 9—9 are connected resembles the ordinary superheater header in almost universal use in this country today. A transverse chamber 11 is in communication with the steam space of the boiler by means of the 80 pipe 12 and the connecting neck 13. From the transverse chamber 11 extend backward the fingers or subsidiary headers 14—14. (See Fig. 2). Alternating with these subsidiary headers 14—14 are subsidiary headers or fingers 15—15 which 85 communicate with the transverse chamber 16. Each superheater unit or element 9 has one of its ends connected to a chamber 14 and its other end to a chamber 15. Steam therefore flows through 90 these elements in parallel from chamber 11 and subsidiary headers 14—14 to be delivered by the elements to the subsidiary headers 15—15 and so to the transverse chamber 16.

To the transverse chamber 16 are secured the 95 first ends of a series of further superheater elements 17—17. The other ends of these units or elements are connected to a transverse chamber 18. From this chamber 18 extend the steam pipes 19—19 which carry the steam to the steam chests. 100

The elements 17—17 are, in the form of the invention shown in Figs. 1 to 6, of the so-called Field-tube type. They extend into and through some of the flues 5, the flues through which they extend being located along the top and sides of the total group of flues. As will be seen from an 110

inspection of Fig. 1, these units 17 extend to a point in the vicinity of the rear end of the fire-box. Steam from chamber 16 flows through the inner tube 21 (see Fig. 5) to the rear end of each 5 unit, this rear end being open as at 22. The outer tube 23 is closed at the rear end by a cap as shown at 24. The steam returns toward the front through the annular space 25 between the inner and outer tubes. At the front it is delivered by 10 means of the end 26 to the chamber 18. Thence, as stated above, it flows to the steam chest.

It will be noted from what has been said above that the steam flows first through the units 9—9 and after having been superheated, flows 15 next through the units 17—17, where it is given its final high superheat. The portion of the units 17—17 which lies in the fire box is exposed to a very intense radiant heat and does a large proportion of the superheating. This location is of 20 course an extremely hazardous one and unless the heat delivered to this portion of the elements is carried off rapidly, these portions will be overheated and fail. It is for this reason that the number of the elements 17—17 is in practice 25 made smaller than the number of the elements 9—9, so that the flow of the steam through the elements 17—17 is more rapid and the heat transfer correspondingly enhanced.

As long as a sufficient amount of steam flows 30 through these elements, no additional protection might be needed. The heat absorption by the steam would in the majority of cases be sufficient to keep the temperature of the metal below the danger point. In locomotive practice, however, 35 the steam flow is of necessity shut off periodically and during such periods when no steam flow occurs through the elements, further protection for the radiant part of the elements 17—17 must be provided. This I do by means illustrated more 40 clearly in Figs. 4, 5 and 6. These means have the further function of supporting the portion of the superheater elements extending into the furnace. This protecting and supporting provision consists essentially of metallic ribs or webs 27. 45 There is one such rib for each superheater element, the rib being arranged parallel to the element and between it and the adjacent fire-box sheet. One edge of each rib 27 is secured, as by welding 28, to the sheet. The other edge is preferably provided with a dove-tail slot 29 (see Fig. 6). Into this dove-tail slot fits slidably the tongue 30 which is integral with or welded to the outer tube 23 of the element. The fit of the tongue 30 in the dove-tail groove 29 is made close so 50 that good heat transfer from one to the other can occur.

Preferably each rib is made in sections separated by spaces as 31—31 (Fig. 1).

By these means the portions of the elements extending into the fire-box are securely supported and protected against overheating. The heat absorbed by the outer tube 23 at times when no steam is flowing through the elements is transmitted through the tongue 30, rib 27 and sheet 55 2 into the water in the boiler. At times when steam is flowing through the unit some heat is similarly transmitted to the boiler water but not sufficient to impair the superheating efficiency of the unit.

The inner tube 21 is kept in proper spaced 70 relation to the outer tube 23 by means of suitable supports or spacers 32—32 which are preferably welded to the inner tube as shown in Fig. 6.

It is usually necessary in locomotives to use 75 auxiliary draft means when the main throttle is

closed and there is no exhaust steam from the main engine to create the draft in the ordinary way. At such times there is of course no steam flowing through the superheater elements but there will be a substantial amount of gases flowing through the flues. In order to protect the radiant units, which are most in need of protection, against damage from gas flowing through the flues in which they lie, I prefer to provide damper means which make it possible to shut off gas flow through those flues in which the units 17—17 are located. For this purpose the front ends of the flues, in which the elements 17—17 lie, open into a space defined by the partition 33. This partition has on each side a damper 34 (only one being shown, see Fig. 3). These dampers are secured to and operated by means of the shaft 35. This shaft is actuated in any preferred manner, either manually or automatically. When the damper 34 is closed, the gas flow through the flues in which the units 17—17 are located is shut off, the units being thereby protected.

In the form of the invention illustrated in Figs. 1 to 6 and just described, the radiant elements are of the Field-tube type. It is however 100 not necessary that they be given this form and the second form of my invention shown in Figs. 7 to 13 uses elements of the ordinary hairpin loop type. In this variation of my invention, the elements located in the fire-box do not extend forward through the flues 5—5 but extend outward through the rear water leg 34. For this purpose thimbles 35—35 of suitable shape are provided which are secured to the two sheets making up the water leg. Each element comprises two legs 110 36—36 united in the front by a return bend 37. The ends which extend through the thimbles 35 are bent toward and connected to the bi-chambered header 38. One end of each element communicates with the chamber 41 and the other with 115 chamber 40. Steam is admitted to one of the chambers, for example 40, by means of a connection 42 and leaves the other chamber by means of the neck 43. The pipes 44 and 45 respectively supply and take away the steam. The elements of this form of superheater are supported and protected by means quite similar to those used in the form first described. A web or rib 120 27a is welded along one edge to the sheet 2 as at 28a. Its outer edge is dove-tailed at 29a and a tongue 30a slidably engages the dove-tailed groove. This tongue is secured in good heat transferring relation, as by welding, to the two tubes 36—36 of the unit. Preferably the web or rib 27a is also made in sections spaced apart as at 125 31a—31a.

The thimbles 35 are of such shape that the space between them and the pipes 36—36 is easily closed up if desired.

It will be understood that the steam supplied to this radiant superheater shown in Figs. 7 to 13 may, if preferred, be given a preliminary superheat in a flue superheater of the ordinary type or any preferred form, or that in some cases the radiant superheater is the only superheater used.

The type of superheater element shown in Figs. 9, 12, and 13 may if preferred also be used in the form of my invention first described, and similarly the Field-tube unit may be used in the second form. Further variations will occur in practicing my invention without departing from its spirit. Among such variations are for example such as would naturally occur if the invention is applied to a locomotive fire-box of the water-tube type.

As to both the arrangements illustrated, it will be seen that the superheater elements and the supports therefor are so arranged that the supports are in large measure shielded by the superheater elements from the radiant heat of the furnace whereby the total heat absorbed by the elements and the supports together is much reduced and the supports are so much the more able to conduct heat from the elements to the water cooled furnace wall.

What I claim is:

1. In apparatus of the class described, the combination of a fire-box having a water-cooled sheet, a superheater comprising a tubular element in proximity to the sheet, and means to protect said tubular element against over-heating comprising a web secured to the sheet and to the tubular element to support the latter and to conduct heat from it to the sheet.
2. The combination claimed in claim 1, the web extending in the same direction as the tubular element and the connection between the two being such that it permits longitudinal relative motion.
3. In apparatus of the class described, the combination of a fire-box having a water-cooled crown sheet, a superheater comprising a plurality of tubular elements in generally parallel arrangement in proximity of the crown sheet, and means to protect said elements against over-heating comprising a web for each element extending between the crown sheet and the element and connecting the two in heat-transferring relation.
4. In a locomotive boiler having a fire-box with a water-cooled crown sheet, a smoke-box, and flues connecting the two, the combination of a superheater header in the upper part of the smoke-box, a plurality of tubular superheater elements with their ends connected to the header and extending through the flues into the fire-box to a point in proximity of the wall opposite the fire-box flue sheet, and means to protect the portions of said elements which are located in the fire-box against over-heating comprising a web for each element extending between it and the crown sheet, parallel to the element, and connected in heat transferring relation to the element and to the crown sheet.
5. The combination according to claim 4 and including further additional means to superheat the steam before it is delivered to the said superheater header and comprising tubular elements located in other flues.
6. Apparatus in accordance with claim 1, the

tubular element comprising an outer tube closed at one end and an inner tube located within the former and spaced from its wall and having an open end adjacent to the closed end of the former, and means to supply steam to the opposite end of one of the two tubes and to take away steam from the opposite end of the other.

80

7. The combination according to claim 1, the tubular element comprising an outer tube closed at one end and an inner tube located within the former and spaced from its wall and having an open end adjacent to the closed end of the former, and means to supply steam to the opposite end of one of the two tubes and to take away steam from the opposite end of the other, the web extending in the same direction as the tubular element and being welded to the sheet and secured to the outer tube by a dove-tail tongue-and-groove joint permitting longitudinal relative motion.

85

8. In apparatus of the class described, the combination of a fire-box having a water-cooled crown sheet and a rear water leg, a plurality of thimbles extending through the water leg, a superheater header adjacent to the outside of the water leg, a plurality of tubular superheater elements connected to the header and extending through the thimbles and along the crown sheet, and means to protect these elements against over-heating comprising a web for each element extending lengthwise of the element between it and the crown sheet and connecting the two in heat-transferring relation and so as to support the element.

90

9. The combination according to claim 1, the web extending in the same direction as the tubular element and the connection between the two being such that it permits longitudinal relative motion, and that the element can be removed by moving it in a longitudinal direction.

95

10. In a locomotive boiler the combination of a furnace including a water-cooled wall, a primary superheater of the smoke flue type comprising tubular elements disposed in the path of gas flow from the furnace, a superheater exposed to furnace radiation serially connected to the primary superheater and comprising tubular elements extending into the furnace adjacent to said wall, a header to which the tubular elements of both of the superheaters are connected, and provisions common to the wall and the radiant superheater elements to pass excess heat from the latter to the wall.
